UNITED STATES PATENT OFFICE.

MEYER W. SCHLOSS, OF NEW YORK, N. Y., ASSIGNOR TO TREO COMPANY, INC., A CORPORATION OF NEW YORK.

BRASSIÈRE.

1,327,408.

Specification of Letters Patent.

Patented Jan. 6, 1920.

Application filed March 29, 1919. Serial No. 286,035.

To all whom it may concern:

Be it known that I, MEYER W. SCHLOSS, a citizen of the United States, residing at the city of New York, in the borough of Manhattan and State of New York, have invented certain new and useful Improvements in Brassières, of which the following is a full, clear, and exact description.

This invention relates to brassières, the object being to provide a construction of brassière which, besides affording the required reducer for the breast, will also serve to compress the front part of the body at or immediately above the waist line. The invention is adapted more particularly for the use of fleshy persons who use in conjunction with the brassière a so-called low corset.

When the corset and brassière are both worn, the corset is first adjusted to the body and the brassière then applied over it, the lower edge of the brassière overlapping the upper edge of the low corset. When the corset is worn by fleshy persons and laced tightly around the body, the tissue of the body is caused to protrude or roll over the upper edge of the corset and some means is desirable to prevent this displacement or protruding of the flesh as it is unsightly and undesirable. The construction of the brassière herein described is adapted particularly for this purpose and its construction in detail will now be described in connection with the accompanying drawing.

Figure 1 is a face view of the improved brassière laid out its full length flat; and

Fig. 2 is a view of the human figure with the brassière in place thereon and associated with a corset.

The front of the brassière to which my improvements are applied consists essentially of the two parts or zones *a* and *b*. The zone *a* is the elastic upper portion used for the ordinary purposes of the brassière, while the lower zone *b* is of comparatively rigid but still elastic material which is applied at or slightly above the waist line. This portion *b* is made elastic in order that the garment may be applied to the body under longitudinal tension and will thereby fit well and smoothly against the body. The brassière is adjusted to the body so that this zone *b* overlaps the upper edge of the low

corset, the corset being indicated in Fig. 2 by *c* and its upper edge by the dotted line 55 *c'*. Immediately above the upper edge of the corset, and directly in front, is the location where the flesh of the body is forced outward most prominently. The elastic material of the zone *b* of the brassière ordinarily is intended to reduce or suppress this protruding tissue, but in many instances it does not accomplish its purpose, and I have therefore provided at the central region of the zone *b* an inelastic or rigid shield *f* which 60 may be of any suitable shape, but which preferably is pointed at the top and extends substantially across the full width of the zone, although this is not essential. I construct this shield either by stitching a piece 70 of coutil or other inextensible material to the face of the elastic material, or I may cut out the elastic material and insert the shield therein by stitching. In any case 75 the presence of this inextensible or inelastic area at the point where the flesh of the body tends to protrude, is sufficient to hold the body flat and give the appearance of a continued even surface from the edge of the corset upward. I do not limit myself either 80 to the size or shape of this shield *f* nor to the extent to which it may encroach upon the zone *b*, but I have found the shape shown in the drawing to be very serviceable for the purpose. It will be understood that the 85 wings *d* and *e* pass around the body and are secured edge to edge at the back and that the brassière may be sustained in position somewhat by the shoulder straps *g*.

I claim:

1. A brassière having in combination a breast zone and below the latter and attached thereto an elastic waist zone, the waist zone having a centrally disposed inelastic section of substantial area to form a reducing pad, as set forth.

2. A brassière having in combination a breast zone and below the latter and attached thereto, an elastic waist zone provided with an inelastic section of substantial area to form a reducing pad, as set forth.

In witness whereof I subscribe my signature.

MEYER W. SCHLOSS.
